UNITED STATES PATENT OFFICE.

DAVID H. STROUD, OF NOBLE, PENNSYLVANIA.

PACKING APPARATUS.

Application filed June 15, 1923. Serial No. 645,497.

To all whom it may concern:

Be it known that I, DAVID H. STROUD, a citizen of the United States, residing at Noble, in the county of Montgomery and State

5 of Pennsylvania, have invented certain new and useful Improvements in Packing Apparatus, of which the following is a specification, reference being had to the accompanying drawings.

10 My invention relates generally to packing apparatus, and more specifically to apparatus advantageous to the textile industry in compacting thread into cops for use in the shuttles of looms.

15 As is well known to those schooled in textile manufacture, it is essential to production of pile fabrics, such as carpets or rugs for instance, that the chenille used as the weft thread be laid in a definite position in the

20 fabrics, and this is especially true when the tufts in the chenille are differently and alternatively colored initially to produce a predetermined pattern in the finished articles. Accordingly, when the chenille is

25 wound into cops in the ordinary manner, it is invariably necessary for the weaver, after each shot of the shuttle, to eliminate all twists before beating the chenille into the fabric.

30 My invention is directed chiefly toward provision of apparatus capable of compacting chenille thread into cops in such manner as to preclude induction of twists, and thereby to eliminate the difficulties above pointed out when used in the shuttles of looms.

35 How the foregoing desideratum may be attained, together with other objects and attendant advantages, will become apparent from the detailed description, which follows, of a typical embodiment of my invention; while the appended claims clearly define the scope of said invention in so far as it comes within my present knowledge.

40 In the drawings Fig. I is an elevation of a packing apparatus conveniently embodying my invention showing the same as it appears when viewed from the front, and with portions thereof broken away and in section to expose certain novel details which would 45 otherwise be concealed.

Fig. II is an end elevation of the apparatus as viewed from the left of Fig. I.

45 Fig. III is a cross-section of the same taken as indicated by the arrows III—III in Fig. I.

Fig. IV is a detail view, on an enlarged

scale, illustrating the manner in which the chenille is packed, in accordance with my invention, into containers provided for its reception.

60 Fig. V is a fragmentary detail, likewise enlarged, of the mechanism for driving the means whereby the chenille is fed and packed into the containers.

Fig. VI is a view showing the details of 65 the clutch mechanism associated with the drive mechanism supra.

Figs. VII and VIII are, respectively, a perspective view, and a longitudinal sectional view of said clutch mechanism.

70 Fig. IX is an illustration, on a larger scale than the others, of the clutch pin forming part of the clutch mechanism; and

Fig. X is a detail view of one of the containers for the chenille.

75 As herein shown, the apparatus includes a frame comprehensively indicated at 1 designed for the support of the various moving parts of the structure. This frame, it will be observed, comprises end members 80

2—2, and a series of longitudinally extending members or beams 3, 4, 5 and 6 which tie together said end members and cooperate to impart the necessary rigidity to the frame.

85 Reciprocating in bearings jointly afforded by the beams 3 and 4 of the frame, are plungers 7 which are aligned with a corresponding number of spaced carriers 8 which serve as holders for containers represented at

90 9, into which the chenille is to be packed. These elements constitute, with other associated parts yet to be described, individual packing units which are exact counterparts of one another so that the description of one

95 will hold for the others. Proceeding therefore, in the singular, the carrier 8 is shown as being generally cylindrical in form, but cut away at the front, as indicated at 10, to permit ready insertion and withdrawal of

100 the container 9. This carrier 8, furthermore, is adapted to recede downwardly as the material accumulates in the container 9, guidance being afforded by a pair of rods 11 rising from anchorage lugs 12 projecting outwardly from the beam 6 as clearly shown in 105 Fig. I.

110 The chenille, indicated by the letter C in the drawings, is fed into the container 9 by a grooved feed roll 13, but before encountering said roll, is drawn over a fixed bar 15 extending longitudinally across the back of the frame 1. The bar 15 is appropriately

notched as at 16 to assist guidance of the chenille C and to remove any twist in the same. The roll 13 is mounted for free rotation upon a shaft 17, and is driven in a manner which will be presently explained. Feeding of the chenille C is assisted by an auxiliary roller 18 which is actuated through the medium of a belt connection 19 with the roll 13 as best seen in Fig. III. In order 10 to permit taking up of the slack in the belt 19, the roller 18 is mounted upon a supporting arm 20 which is adjustably set upon a fixed rod 21 extending longitudinally between the end members 2—2 of the frame 1. 15 The chenille C fed as above noted, is directed into the container 9 in the carrier 8 through a funnel-like chute 22 having in its wall a channel 23 for guiding said chenille, in a definite direction, in the course of 20 its passage into the container 9. Such guidance of the chenille C is further assisted through provision of a longitudinal groove 24 in the lower end of the plunger 7 to register with the groove 23 as seen to the 25 best advantage in Fig. IV, said groove 24 also serves as a clearance to permit free forward movement of the chenille C during the retractive strokes of the plunger 7. 30 The recession of the carrier 8, compensatively, as the material accumulates in the container 9, is opposed by a counterweight 25, which is attached to the end of a flexible connector in the form of a cord or cable 26. This cord or cable 26 passes about an idler 35 pulley 27 supported between spaced, rearwardly projecting lugs 28 of the beam 5. The other end of the connector or cord 26 is tied to a hooked lug 29 on the back of the carrier 8. For the purpose of maintaining 40 the carrier 8 in its successive shifted positions, I provide a check in the form of a sector clamp 30, see Fig. IV, which is fixed to a shaft 31 journalled between the lugs 28 already referred to, directly above the pulley 27. This check 30, it will be noted, has an 45 eccentric edge 32 adapted to bind the cord or cable 26 within the groove of the pulley 27, such binding action being prompted by a weighted lever 33 secured on the same 50 shaft with said sector. As a result of this arrangement, the pulley 27 is free to rotate in correspondence with the downward movement of the carrier 8, but retrograde movement thereof is checked to hold said 55 carrier in successive shifted positions while the plunger 7 moves away from the same during its upward idle strokes. At its outer end, the weighted lever 33 has a finger 60 grasp 34 whereby it may be readily lifted to trip the check 30, thereby removing all restraint upon the pulley 27 and allowing the weight 25 to automatically restore the carrier 8 to its normal or starting position after a new container 9 has been substituted 65 therein for one previously filled.

The mechanism for reciprocating the plunger 7 includes an overhead rocker arm 35 mounted to oscillate freely upon a fixed longitudinal fulcrum bar 36 extending between the frames 2—2, said arm 35 being connected at one end, by means of links 37, to opposite sides of a collar 38 fixed at the top of the plunger 7. A weight 39 formed on the opposite end of the lever 35 serves as a counter-balance for the plunger 7 to 70 stabilize its movements, and a coiled spring 40, attached at one end to the counterweight 39, and at the other, to a fixed anchorage 41 of the framework 1, functions to retract the plunger 7 on its idle strokes. The down 75 strokes of the plunger 7 are effected by virtue of the connection of the lever 35, through the medium of a flexible band 42, with a drum 43 mounted for free rotation upon a fixed shaft 44 supported in suitable bearings on the end members 2—2 of the frame 1. The lower end of the flexible connector 42 is secured by screws or their equivalents indicated at 45, to the radial edge of an angular cut in the drum 43 as best seen 80 in Fig. V of the drawings. Through oscillations of the drum 43 induced as herein-after explained, the connector 42 is alternately wound upon, and unwound from the 85 drum, in the first instance drawing upon the arm 35 to determine the down or active stroke of the plunger 7, and, in the other instance, yielding to the spring 40 whereby 90 said plunger is retracted. Slight excess movement accorded the drum 43 allows a 95 certain amount of slack in the flexible connector 42 and thereby defines a dwell, directly after the plunger 7 reaches the limit 100 of its upward strokes, which is determined by contact of the collar 38 with the guide bearing of the rail 3. The time interval thus afforded will permit feeding of an excess length of chenille C before the plunger 105 7 descends so that folds are formed as a consequence as shown in Fig. IV. 110

The drum 43 receives its motion from the main drive or power shaft 46 of the machine through a clutch mechanism and interposed connections about to be described. Fixed 115 to the power shaft 46 is a collar 47 having a lug projection 48 adapted to engage with a sectoral lug 49 at the end of a clutch pin 49^a, (see Figs. VII and VIII), carried by a gear 50. This gear 50 in turn drives an intermeshing gear 51 supported by a bracket 120 52 hung between the shaft 44 and the power shaft 46. The gear 51 has a crank pin 53 which projects from the side remote from the observer in Fig. V, and is connected by means of a link 54 to a similar crank pin 55 125 on the near side of the drum 43. By this arrangement rotation of the gear 51 is translated into oscillations of the drum 43. Attention is now directed to Fig. VIII wherefrom it will be seen that the clutch pin 49^a 130

has an axial cavity for the accommodation of a spring 56 which tends to maintain the pin in its projected position and therefore in the path of the lug 48 of the collar 47. 5 So long as this engagement exists the plunger 7 will be continuously reciprocated and the chenille C concurrently therewith, continuously fed, the latter by reason of a belt connection 57 between the gear 50 and 10 the roller 13 over which said chenille travels. For the purpose of automatically suspending the activity of these parts when the container 9 has been filled, I provide means for causing the disengagement of the clutch 15 members 48, 49 when the carrier 8 has receded to a predetermined extent. This mechanism includes a draw bolt 60 guided for longitudinal shifting, jointly by a boss 61 on the bracket 52 previously referred to, 20 and a lug 62 depending from the longitudinal cross rail or bar 6 of the frame 1. When the draw bolt 60 is projected to the left as considered in Fig. V its inner end intercepts the clutch pin 49^a, and, by engaging a cam 25 surface 63, (see also Figs. VII, VIII and IX) at the end of the latter directly adjacent the lug 49, forces the same into its retaining cavity in the gear 50 and thereby effects its removal from the province of the 30 lug 48 of the collar 47. When this happens, it will be seen that the drive mechanism is rendered inactive thereby causing feeding of the chenille C to cease, and simultaneously therewith, suspension in the movements of the 35 plunger 7. Referring again to Fig. V, a spring 65 compressed between the lug 62 and a collar 66 on the rod 60, tends to urge said rod inward, and when the drive mechanism is to be maintained in activity, this 40 tendency is opposed by a latch 67 which engages behind a shoulder afforded by a grasp knob 68 at the outer end of said rod. The latch 67 is pivoted for free movement about a stud 69, and is counterweighted as at 45 (see Fig. I) so as to be urged at all times into the active position shown in the drawings. This latch 67 is further provided with a projection 71 which lies within the path of a stop 72, (see Fig. IV) adjustably 50 set in, and depending from a lug 73 of the carrier 8. Thus, as the carrier 8 moves downwardly, the stop 72, by engaging the projection 71 swings the trip 67, thereby 55 effecting release of the rod 60, which, under the compressive force of the spring 65, is thrust inwardly so that its forward end engages the clutch pin 49^a as already noted to render the drive mechanism idle. 60 Both from the standpoint of convenience in handling, and that of greater longevity, I prefer to construct the container 9 in bag form from flexible material, for example burlap or the like. A container 9 so made will, on the one hand, accommodate itself 65 readily to the shape of the carrier 8, and on the other, when filled, may be readily inserted in the cavity of a loom shuttle. Collapse of the container 9 and its displacement otherwise in the carrier 8, is prevented by provision of a ferrule 75 secured about the 70 open end or mouth of the bag and adapted to support the same in suspension from the top of the carrier 8. The said ferrule 75, as best shown in Figs. IV and X, comprises two annular parts 76, 77, the one provided 75 with a tapered prolongation 78 adapted to be telescopically received in the other and to clamp between them, the margin of the fabric about the mouth of the bag. A depending tubular prolongation 79 of the funnel guide 22, serves to maintain the bag or container 9 open thereby facilitating the feeding thereinto of the chenille C, and, by its interposition, prevents said bag from being pulled out of the carrier 8 during the 80 retractive strokes of the plunger 7. 85 The chenille C may be drawn under the action of the feed roll 13 from any convenient source of supply, provided however that a proper degree of tension is maintained thereon in order to prevent excessive slack. 90 As an example of means suitable to this end, attention is once more directed to Figs. II and III of the drawings. The chenille C is initially prepared preferably by winding the same upon a reel or beam 80, one such being provided for each unit of the machine. This reel or beam 80 is mounted between a pair of supporting brackets 81 bolted or otherwise secured to the machine frame and 95 extending laterally outward from the rear thereof as shown. The desired tension may be induced and maintained by means of adjustable screws 82 let into the journals of the brackets 81 and bearing against the shaft 83 100 of the reel or beam 80 aforesaid. 105 The operation of my improved packing apparatus is as follows: 110 Assuming, (as is suggested in the drawings), that the various parts of the apparatus are in motion, it will be seen in view of the constant feeding of the chenille C, and by virtue of the dwell periods in the movements of the plunger 7, that folds will be successively formed in the chenille C and 115 the latter thus packed in the container 9, the direction of laying of such folds being predetermined by the cooperation of the directing groove 23 in the funnel guide 22 and the longitudinal slot 24 in the plunger 7. Packing of the material proceeds until the container 9 is filled and when the carrier 8 for said container has receded to the extent necessary to bring about the engagement of the stop 72 with the trip 67, thereby releasing 120 the bolt 60 to the action of the spring 65 and causing the disengagement of the clutch members 48, 49 as already understood. Thereupon, feeding of the chenille C and the 125 operation of the plunger 7 immediately 130

ceases, the carrier 8 with the filled container 9 remaining in the lowered position so that said container may be removed and replaced by a new one. The latter act is accomplished by first placing the ferrule 75 about the top of the container bag and drawing the same over the tubular extension 79 of the funnel guide 22, said extension being at this time exposed due to the maintenance of the carrier 8 in its lowered position. When the new container 9 has been properly placed in the carrier 8, the operative, by grasping the finger projection 34 on the lever 33 associated with the check 30, releases the pulley 27 and thereby permits the weight 25 to elevate the carrier 8 to the original or starting position. The driving mechanism may then be set in motion by grasping the knob 68 and drawing upon the bolt 60 so that the inner end of the latter is retracted from the path of the clutch pin 49^a when the parts of the drive mechanism will again assume the relations shown in Fig. V. As the bolt 60 is drawn as above noted the latch 67 automatically slips, under the influence of gravity, behind the head 68 to detain the bolt 60 in the drawn position until again released when the new bag has in its turn been filled. The above remarks of course hold good for each packing unit comprised in the apparatus, and, since individual drive means are provided for these units, one is entirely independent of the other, so that cessation of one for inter-change of containers, does not interfere with operation of the others.

While I have herein shown and described my invention as especially suited to packing material in thread form, it is obvious that the same may be employed with equal advantages, and without departing from the spirit of my invention, in packing a great many other materials or substances which need not be specifically mentioned.

Having thus described my invention, I claim:

1. In apparatus of the character described, the combination of a container, grooved means for feeding and guiding material in thread form thereto, and associated grooved means for packing said material in the container with uniform successive folds.

2. In apparatus of the character described, the combination of a container, a grooved feed roll and grooved chute for respectively feeding and guiding material in thread form thereto, and grooved means intermittently cooperative therewith, whereby the material is packed with uniform successive folds.

3. In apparatus of the character described, the combination of a container, a grooved feed roll and associated grooved chute for directing material in thread form

thereto, and a longitudinally grooved packing means cooperative with said directing means to determine the laying of the material in uniform successive folds.

4. In apparatus of the character described, the combination of a container, a grooved feed roll and aligned grooved chute for directing material in thread form thereto, a longitudinally grooved plunger cooperative with said directing means to determine the laying of the material in uniform successive folds, and a carrier for the container capable of automatic recession after each consecutive fold of material is compressed therein.

5. In apparatus of the character described, the combination of a reciprocating grooved plunger, a grooved feed roll and chute cooperative therewith to determine the packing of material in thread form into a container with uniform successive folds, a carrier for the container capable of receding as the material accumulates in the container, means tending to oppose movement of the carrier, and a check operative upon the latter means for the purpose of maintaining the carrier aforesaid in successive shifted positions during the retractive strokes of the plunger.

6. In apparatus of the character described, the combination of a reciprocating grooved plunger, a grooved feed roll and chute cooperative therewith to determine the packing of material in thread form into a container with uniform successive folds, a carrier for the container capable of receding as the material accumulates in the container, a counterweight tending to oppose movement of the carrier, and a check operative upon the counterweight for the purpose of maintaining the carrier aforesaid in successive shifted positions during the retractive strokes of the plunger.

7. In apparatus of the character described, the combination of a reciprocating grooved plunger, a grooved feed roll and chute cooperative therewith to determine the packing of material in thread form into a container with uniform successive folds, a carrier for the container capable of receding as the material accumulates in the container, a counterweight tending to oppose movement of the carrier, a flexible cord whereby the counterweight is connected to the carrier, a pulley over which the cord is guided, and a gravity fall-sector clamp allowing rotation of the pulley to permit free recession of the carrier but preventing movement of the pulley during retractive strokes of the plunger so that the carrier is maintained in its successive shifted positions.

8. In apparatus of the character described, the combination of a reciprocating grooved plunger, a grooved feed roll and chute cooperative therewith to determine the pack-

- ing of material in thread form into a container with uniform successive folds, a carrier for the container capable of receding as the material accumulates in the container, 5 a counterweight tending to oppose movement of the carrier, a check operative upon the counterweight for the purpose of maintaining the carrier aforesaid in successive shifted positions during the retractive strokes of the 10 plunger, and means whereby the check may be tripped to permit return of the carrier to its original or starting position upon the substitution therein of an empty container for one previously filled.
- 15 9. In apparatus of the character described, the combination of a reciprocating grooved plunger, a grooved feed roll and chute cooperative therewith to determine the packing of material in thread form into a container with uniform successive folds, a carrier for the container capable of receding as the material accumulates in the container, a counterweight tending to oppose movement of the carrier, a flexible cord whereby 20 the counterweight is connected to the carrier, a pulley over which the cord is guided, check means allowing rotation of the pulley to permit free recession of the carrier but preventing movement of the pulley during 25 retractive strokes of the plunger so that the carrier is maintained in its successive shifted positions, and devices whereby the brake means may be released to permit automatic return of the carrier to its original or starting 30 position upon substitution therein of an empty container for one previously filled.
10. In apparatus of the character described, the combination of means for continuously directing material in thread form 40 into a container, a cooperative reciprocating grooved plunger adapted to pack the material in said container with uniform successive folds, and actuating means for the plunger defining a dwell at the end of the retractive strokes of said plunger to afford a time interval for sufficient excess feeding of the material to determine the aforesaid fold previous to each descent of said plunger 45 into the container.
11. In apparatus of the character described, the combination of means for feeding material in thread form, a longitudinally grooved channel guide for directing the material into a container and to determine laying of said material with uniform successive folds in one direction only, and a longitudinally grooved plunger for compressing the successive folds compactly in the container. 55
12. In apparatus of the character described, the combination of means for feeding material in thread form, a channel guide for directing the material into a container and to determine folding of the material 60 uniformly in one direction only, and a plunger for compressing the successive folds compactly in the container, said plunger having a longitudinal clearance groove registering with the channelled guide so that withdrawal of the material from the container is prevented during retractive strokes of the plunger. 70
13. In apparatus of the character described, the combination of a plunger for packing material into a container, and means for reciprocating the plunger including a rocker arm, an oscillating drum, a flexible connector attached to the arm aforesaid and adapted to be wound upon the oscillating drum to determine movement to the plunger in one direction, and yielding means operative to take up the slack of the flexible connector while being unwound from the drum and to determine movement of the plunger in the opposite direction. 75
14. In apparatus of the character described, the combination of means for packing material in thread form into a container with uniform successive folds said 80 container having a ferrule comprising telescopic parts between which the mouth of the container is clamped, a carrier for the container capable of receding as the material accumulates in the container, means for maintaining the container open during filling, and mechanism for rendering the packing means aforesaid automatically inactive when the container is full. 85
15. In apparatus of the character described, the combination of means for packing material in thread form into a container with uniform successive folds, said container including a ferrule comprising telescopic annuli having tapered co-operative 90 parts between which the container mouth is clamped, a carrier for the container capable of receding as the material accumulates in the container, a tubular insert for maintaining the container expanded during filling and mechanism coordinated with the carrier for rendering the packing means aforesaid automatically inactive when the container is full. 95
16. In apparatus of the character described, the combination of mechanism for packing material in thread form into a container with uniform successive folds, said container including a telescopic ferrule in which the container mouth is securely 100 clamped, mechanism including a control clutch for actuating the packing means, an associated clutch disengaging means, a carrier for the container aforesaid capable of receding as the material accumulates in the container and an adjustable stop on said carrier adapted to automatically trip the clutch disengaging means for the purpose of rendering the packing mechanism idle 105 when the container is full. 110
17. In apparatus of the character described, the combination of means for feeding material in thread form, a channel guide for directing the material into a container and to determine folding of the material uniformly in one direction only, and a plunger for compressing the successive folds compactly in the container, said plunger having a longitudinal clearance groove registering with the channelled guide so that withdrawal of the material from the container is prevented during retractive strokes of the plunger. 115
18. In apparatus of the character described, the combination of a plunger for packing material into a container, and means for reciprocating the plunger including a rocker arm, an oscillating drum, a flexible connector attached to the arm aforesaid and adapted to be wound upon the oscillating drum to determine movement to the plunger in one direction, and yielding means operative to take up the slack of the flexible connector while being unwound from the drum and to determine movement of the plunger in the opposite direction. 120
19. In apparatus of the character described, the combination of means for packing material in thread form into a container with uniform successive folds said container having a ferrule comprising telescopic parts between which the mouth of the container is clamped, a carrier for the container capable of receding as the material accumulates in the container, means for maintaining the container open during filling, and mechanism for rendering the packing means aforesaid automatically inactive when the container is full. 125
20. In apparatus of the character described, the combination of means for feeding material in thread form, a channel guide for directing the material into a container and to determine laying of the material with uniform successive folds in one direction only, and a longitudinally grooved plunger for compressing the successive folds compactly in the container. 130

17. In apparatus of the character described for packing material in thread form into a container with uniform successive folds, the combination of mechanism for actuating said packing means including a clutch, a spring influenced draw bolt associated with the clutch, a latch adapted to engage behind a shoulder of the draw bolt when the clutch is set, a carrier for the container aforesaid capable of receding as the material accumulates in the container, and an adjustable stop on the carrier adapted to automatically trip the latch, thereby to release the draw bolt and effect disengagement of the clutch for the purpose of rendering the packing means idle when the container is full.

18. In apparatus of the character described for packing material in thread form into a container with uniform successive folds, the combination of mechanism for actuating the packing means including a power shaft, a drive collar fixed to the shaft, a member mounted for free rotation on the shaft adjacent the collar, a clutch pin carried by the member and normally maintained laterally projected under spring pressure to engage with a lug on the drive collar, and a clutch control bolt adapted by being thrust into the path of the clutch pin to contact with a cam surface in the end of said pin for the purpose of displacing the same from the province of the drive collar, and thereby rendering the packing means idle when the container is full.

19. In apparatus of the character described for packing material in thread form into a container with uniform successive folds, the combination of mechanism for actuating the packing means including a power shaft, a drive collar fixed to the shaft, a member mounted for free rotation

on the shaft adjacent the collar, a clutch pin carried by the member and normally maintained laterally projected under spring pressure to engage with a lug on the drive collar, a clutch control bolt adapted by being thrust into the path of the clutch pin to contact with a cam surface in the end of said pin for the purpose of displacing the same from the province of the drive collar, a spring normally tending to thrust the bolt forward, a gravity fall latch adapted to engage behind a shoulder of the bolt to maintain the same retracted, and an adjustable stop on the carrier aforesaid for automatically tripping the latch when the container is filled for the purpose of bringing about disengagement of the clutch elements and consequent inactivity of the packing means.

20. In apparatus of the character described, the combination of a series of mechanisms for packing material in thread form into a corresponding number of containers with uniform successive folds, said containers each having a telescopic mouth gripping ferrule applied thereto, an associated series of individual carriers for the containers capable of receding independently of one another as the material accumulates in the containers, an associated control clutch and disengaging mechanism for each carrier, and means adapted to be actuated individually by the carriers for tripping the disengaging mechanism and rendering their associated packing means idle when the corresponding containers are filled.

In testimony whereof, I have hereunto signed my name at Philadelphia, Pennsylvania, this 13th day of June, 1923.

DAVID H. STROUD.
